CUTTING DEVICE

Harry P. Troendly, Chicago, Ill., assignor to The
Wm. D. Gibson Company, Chicago, Ill., a cor-
poration of Illinois

Application April 4, 1932, Serial No. 603,106

11 Claims. (Cl. 31—27)

This invention relates to a cutting device and a method of assembling the same and has special reference to a device for cutting cheese, butter, and the like, into slices of predetermined thicknesses.

More particularly, this invention has reference to a cutting device and a method of assembling the same, the cutting device comprising a frame having a cutting member disposed thereacross and a guide roller mounted to rotate therein. The frame is preferably stamped or otherwise formed from a single sheet of metal.

The present invention contemplates the provision of a cutting member in the form of a wire held under tension between ears formed preferably integrally with a frame member and a guide roller mounted to rotate on bearing members likewise formed preferably integrally with the frame member. The frame member is formed of a single sheet of material having a handle portion and a U-shaped extending portion between the arms of which latter the guide roller and cutting member are disposed, the frame being suitably strengthened and given an attractive finished appearance in the provision of a marginal beading therearound. The guide roller and cutting member are disposed between the arms of the frame while the positioning members therefor are in an initial position, whereafter the positioning members are moved to a changed position to secure the roller and cutting member in place.

A device of the above character built in accordance with the teachings of this invention may be manufactured at an extremely low cost and the resultant construction is very simple and durable. The operation of the device is conducted with a maximum of efficiency, the roller being guided readily along the surface of the material to be cut and the cutting member being held in a fixed relation therewith to sever a piece of a predetermined thickness.

One of the objects of this invention is to provide a device of the character noted above which is extremely inexpensive to manufacture, is simple in design and operation, is efficient in operation and is durable.

Another object of this invention is to provide a device of the type indicated above in which the frame is formed of a single piece of reenforced sheet metal.

A further object of this invention is to provide a device as recited hereinbefore in which the securing members for the guide roller and cutting member are formed integrally with the frame member.

Other objects and advantages will hereinafter be more fully pointed out and for a more complete understanding of the characteristic features of this invention reference may now be had to the following description when taken together with the accompanying drawing, in which latter:

Figure 1 is a front elevational view of the device embodying the features of this invention;

Fig. 2 is an enlarged detail sectional view taken on the line 2—2 of Figure 1, showing the cutter element in an initial position in full lines and in a changed secured position in dotted lines;

Fig. 3 is an enlarged sectional view with a portion of the roller and cutting member broken away showing an initial position of the roller member prior to its being assembled in the frame;

Fig. 4 is a view similar to Fig. 3 taken on the line 4—4 of Figure 1, showing the roller in an assembled condition;

Fig. 5 is an enlarged sectional view taken on the line 5—5 of Figure 1;

Fig. 6 is a view similar to Fig. 4 of a fragmentary portion of the device therein shown illustrating a modified form of support; and

Fig. 7 is a fragmentary sectional view showing a modified form of assembly, an initial position thereof being shown in full lines and a changed position thereof being shown in dotted lines.

Referring now more particularly to the drawing, the device of this invention comprises a frame 10 having a cutting member 11 and a guide roller 12 supported thereby. The frame 10 is preferably stamped or otherwise formed from a single sheet of metal and comprises a handle portion 13 and a U-shaped portion extending therefrom and preferably integrally formed therewith, the U-shaped member having a body portion 14 with arms 15 and 16 extended therefrom.

The arms 15 and 16 are spaced to receive therebetween the cutting member 11 and the guide roller 12. The frame, including the U-shaped portion and the handle portion, is rigid and in order to give a suitable strength to the comparatively light weight sheet metal employed and also in order to furnish an attractive finished appearance, a marginal beading 17 is provided on the outside of the frame. Of course, it is to be understood that this reenforcing portion may be disposed intermediate the edges of the frame member or on the inside of the frame member as desired, it being shown in the drawing merely for purposes of illustration that a desirable construction may be had by providing the bead around the outside marginal portion of the frame.

In order to secure the cutting member 11 in a

fixed position relatively to the frame, the ends of the cutting member preferably in the form of a wire are tied over or otherwise secured to ears 18 and 19 preferably serrated and deformed from an intermediate portion of the materials of the respective arms 15 and 16. The ears 18 and 19 extend in the instance shown in the drawing substantially at right angles to the surfaces of the arms in an initial condition. However, this initial degree of angularity is not important in that the ears may be set at various degrees with respect to the surfaces of the arms or with respect to a plane vertical to the surfaces thereof, whereafter the angularity is changed by moving the ears in a direction away from each other to increase the tension on the cutting member to any desired degree.

In the assembly of the cutting member 11 to the device, loops may first be formed at the ends 20 of the wire or apertures, and such loops, hooks, or apertures may then be engaged with the ears when the latter are in an initial position. A suitable die may be employed to move the ears in a direction away from each other until a desired degree of tension is had on the cutting member. Of course, it is to be understood that it is not necessary to have the ears at the same relative angles with respect to the arms since one may be fixed initially at the position to which it will ultimately be in use and the tension be brought upon the cutting element in the change of degree of angularity of but one of the ears. Thus, for example, the ear 19 may be bent initially into its dotted line position in Fig. 2 and the ear 18 be given 35 its position as shown in full line in Fig. 2, whereafter merely the movement of the ear 18 to its dotted line position will provide a sufficient tension on the cutting member. Should the cutting element become loosened to any degree after use 40 in cutting, the user, in order to give the cutting member a desired tension, would merely have to strike either or both of the ears a blow to provide a sufficient amount of tension thereon.

In order to definitely locate the cutting element, 45 if a wire be used as such, portions 20 and 21 may be formed preferably integrally with the arms 15 and 16, respectively, the projecting portions extending upwardly out of the planes of the surfaces 50 of the arms and being provided with notches with which the wire engages. The loops of the wires extend over the ears 18 and 19 and contact 55 with shoulder portions which are preferably formed on the ears to locate the loops, the wire passing from the ears over the projecting portions 20 and 21 in the notches thereof.

In order to secure the guide roller 12 in position with respect to the frame, bearing portions 22 and 23 are provided on the arms 15 and 16, respectively. These members 22 and 23 are preferably formed integrally with the arms 15 and 16, respectively, and project downwardly and inwardly therefrom. The downwardly projecting portions 24 and 25 are preferably of substantial width at the juncture thereof with their respective arm portions and converge to the inwardly extending portion of the bearings, the inwardly extending portions 26 and 27 being formed of annular lateral cross-section. The portions 26 and 27 are preferably formed into their annular shape from a strip formed integrally with the downwardly extending portions 24 and 25 and the arms 15 and 16, the strips being rounded into such annular form with a central opening 75 for receiving studs 28 and 29, respectively,

extending from the ends of the guide roller 12 axially thereof.

Referring now to Fig. 6 of the drawing, it will be noted that in place of the annular bearings receiving the studs 28 and 29, respectively, extending from the ends of the guide roller, the latter may be provided with an aperture for receiving the bearing portions 26 and 27. 5

The bearing portions 26 and 27, as hereinabove stated, extend inwardly from depending portions 10 of the arms 15 and 16, respectively, or, it may be said they extend in a direction toward each other. However, in order to permit the guide roller 12 to be assembled therein, since the frame member is of rigid construction, the bearing portions 15 26 and 27 extend at an angle to the horizontal or at least one of the bearings may be so disposed whereafter the bearing or bearings may be moved into a single plane coaxial with the studs 28 and 29. In changing the angularity 20 of the bearing members 26 and 27, the distance therebetween is considerably shortened and, of course, such distance is predetermined in order to permit of a desired fit.

In the instance shown in Fig. 3 of the drawing, 25 both bearing members 26 and 27 are disposed angularly relatively to the horizontal and the guide roller 12 together with its extending stud portions are just permitted to engage the apertures in the bearing portions and come to a stop 30 against the upper ends thereof. The bearing portions are then forced upwardly into axial alignment with each other and with the axis of the guide roller preferably by the same die members and in the same operation as that of 35 changing the angularity of the ears 18 and 19, the movement shortening the distance, of course, between the bearing portions and coming to rest with just sufficient play between the ends thereof and the ends of the guide roller to permit of a 40 desired rotation of the latter. It is, of course, to be understood that it is only necessary to change the angularity of one of these bearing portions, although, it has been found to be desirable in order to conveniently employ one form 45 of die member to have the angularities in both of the bearing portions. The bearing portions are suitably reenforced in the provision of beaded portions extending intermediate of the downwardly extending portions 24 and 25 and continuing into the supporting arms as shown at 50 30 and 31.

With reference to the embodiment shown in Fig. 6, the bearing members 26 are disposed angularly relatively to the horizontal and the guide 55 roller 12 is moved into position such that the bearings are permitted to engage the apertures in the guide roller and come to a stop against the upper surfaces bounding the aperture. The bearing portions are then forced upwardly into axial alignment with each other in the same manner as aforesaid, the movement shortening the distance, of course, between the bearing portions and coming to rest within the apertures with just sufficient play to permit of a desired rotation of the 60 roller. 65

I have above described that the bearing members themselves may be angularly disposed relatively to the horizontal, although it may be desirable to angularly dispose the main body portion of the arm angularly relatively to the horizontal, as shown more particularly in Fig. 7 in full lines. The body portion of the arm or arms, depending upon whether both arms or just one 70 thereof is disposed angularly, is then forced up- 75

wardly in the same manner as the bearings previously described to obtain an axial alignment of the bearings with each other and the axis of the guide roller.

5 As a result of this invention, a construction is provided which may be manufactured at an extremely low cost, the construction being very simple and durable. The operation of the device is conducted with a maximum of efficiency and the 10 method of assembly permits of a relatively low cost.

While but a single embodiment of this invention is herein shown and described, it is to be understood that various modifications thereof 15 may be apparent to those skilled in the art without departing from the spirit and scope of this invention and, therefore, the same is only to be limited by the scope of the prior art and the appended claims.

20 I claim:

1. A cutting device comprising a rigid frame having spaced arms extending from a body portion thereof, a guide roller and a cutting member extending between said arms, an ear serrated and deformed from the material of each of said arms for securing the ends of said cutting member, and means for supporting said guide roller.

2. A cutting device comprising a rigid sheet metal frame having spaced arms extending from 30 a body portion thereof, a guide roller and a cutting member extending between said arms, means on each of said arms for securing the ends of said cutting member, projecting means formed integrally with said arms for predetermining the 35 location of said cutting member, and means for supporting said guide roller.

3. A cutting device comprising a sheet metal rigid frame having spaced arms extending from a body portion thereof, a guide roller and a cutting member extending between said arms, an ear formed integrally with each of said arms for securing the ends of said cutting member, projecting means formed integrally with said arms for predetermining the location of said cutting member, and means for supporting said guide roller.

4. A cutting device comprising a rigid frame having spaced arms extending from a body portion thereof, a guide roller and a cutting member extending between said arms, an ear serrated and deformed from an intermediate portion of the material of each of said arms for securing the ends of said cutting member, a notched lip formed integrally with and raised out of the plane of each of said arms, said cutting member engaging 55 said notches for predetermining the location thereof, and means for supporting said guide roller.

5. A cutting device comprising a rigid sheet metal frame having spaced arms extending from 60 a body portion thereof, a guide roller and a cutting member extending between said arms, means on each of said arms for securing and locating the

ends of said cutting member, and portions formed integrally with and projecting from said arms of annular cross-section forming bearings for supporting said guide roller.

6. A cutting device comprising a rigid sheet metal frame having spaced arms extending from a body portion thereof, a guide roller and a cutting member extending between said arms, means on each of said arms for securing and locating the ends of said cutting member, and reenforced portions formed integrally with and projecting from said arms of annular cross-section forming bearings for rotatably supporting said guide roller.

7. A cutting device comprising a rigid frame formed of sheet metal having a handle portion 15 and a U-shaped extending portion, a guide roller and a cutting member extending between arms of said U-shaped portion, means formed integral- 20 ly on each of said arms for securing and locating the ends of said cutting member, and projecting portions formed integrally with said arms for forming bearings for supporting said guide roller.

8. A method of assembling a cutting device having a rigid sheet metal frame including spaced arms for supporting a cutting member consisting in disposing said cutting member between ears formed integrally with said arms and projecting at an angle to said frame, and in changing the angularity of at least one of said ears by bending the material thereof to increase as desired the 30 amount of tension on said cutting member.

9. A method of assembling a cutting device having a rigid sheet metal frame including spaced arms for supporting a cutting member consisting in securing said cutting member between ears 35 formed integrally with said arms and projecting at an angle to said frame, and in moving said ears in a direction away from each other by bending the material thereof to increase the tension on said cutting member.

10. A method of assembling a cutting device having a rigid sheet metal frame including spaced arms for supporting a guide roller and a cutting member consisting in disposing said roller between bearing members formed integrally with 45 said arms projecting at an angle, and in changing the angularity of at least one of said bearing members to secure said roller on said bearing members by bending the material thereof.

11. A method of assembling a cutting device having a rigid sheet metal frame including spaced arms for supporting a guide roller and a cutting member consisting in disposing said roller between bearing members formed integrally with 50 said arms extending from said arms in a direction angularly toward each other, and in changing the angularity of at least one of said bearing members by bending the material thereof to a 55 position such that they are substantially coaxial to secure said roller thereon.

HARRY P. TROENDLY.
